UNITED STATES PATENT OFFICE.

FREDERICK W. LUSCOMB, OF NEW BEDFORD, MASSACHUSETTS, ASSIGNOR TO ATLAS TACK COMPANY, OF FAIRHAVEN, MASSACHUSETTS, A CORPORATION OF NEW JERSEY.

HOOK-SETTING MACHINE.

1,209,864.

Specification of Letters Patent.

Patented Dec. 26, 1916.

Application filed October 8, 1915. Serial No. 54,773.

To all whom it may concern:

Be it known that I, FREDERICK W. LUSCOMB, a citizen of the United States, and resident of New Bedford, in the county of 5 Bristol and State of Massachusetts, have invented certain new and useful Improvements in Hook-Setting Machines, of which the following is a specification.

This invention relates to machines for setting lacing hooks, and consists in features 10 relating to the hook-transferring means, and to the timing of the hook-sustaining member and the setting tool whereby the latter is caused to relieve the pressure on a set hook 15 but to remain in the shank of the set hook to hold the work while the hook-sustaining member is being withdrawn from the hook.

Of the accompanying drawings: Figure 1 represents a front elevation, partly in section, of a hook-setting machine embodying 20 the present invention. Fig. 2 represents a side elevation, partly in section, of the front portion of such machine. Fig. 3 represents a section, in a horizontal plane, of a mechanism which feeds the work. Fig. 4 represents a vertical section, on a larger scale, of the coöperative hook-setting elements in the 25 act of setting a hook. Fig. 5 is a view similar to Fig. 4, showing the setting tool raised slightly above the position shown by Fig. 4 and showing the hook-sustaining member as having been withdrawn from the set hook. Fig. 6 represents a side elevation of the operating mechanism which imparts 30 movement to the setting tool. Figs. 7 and 8 show the two coöperative cams which are included in Fig. 6. Fig. 9 is a front elevation of the crank-disk and crank-pin which transmit motion from the operating mechanism shown by Fig. 6 to the setting tool, 35 and includes broken lines indicating the several angular positions at which the crank-pin dwells.

The same reference characters indicate the 40 same parts wherever they occur.

The setting tool in the present instance is provided with a central projection which coöperates with a punch-block to punch a hole in the work. At the time of the punching operation the setting tool is at one side of its setting position, and after the punch has been brought to bear on the punch-block it is raised enough to relieve the pressure on the punch-block but not enough to withdraw the 45 punch from the work. While the punch re-

mains in the hole which it has formed in the work the setting tool is moved laterally to its setting position, thereby feeding the work to the desired position for receiving a hook. The hook-sustaining member in the meantime receives a lacing hook from suitable hook-feeding means below the work and is raised to pass the shank of the hook through the punched hole in the work and to clench the hook against the setting tool. When 60 the setting operation has been completed the setting tool is raised sufficiently to relieve the pressure upon the set hook but not enough to withdraw the punch from the shank of the hook; and while the setting 65 tool remains in this position to hold the work by means of the set hook, the hook-sustaining member is withdrawn from the hook.

The setting tool is indicated at 10, and the 70 punch formed thereon is indicated at 11. This tool is carried by a vertically movable plunger 12, and the plunger is arranged to slide in a sleeve 13 formed upon a sliding carriage 14. The carriage moves from side 75 to the side on dovetailed guides 15, 15 to feed the work.

The punch-block which coacts with the punch is indicated at 16. A presser-foot 17 is arranged to coact with the punch-block 80 and is operated by suitable mechanism which causes it to release the work for feeding but to clamp the work at other times. The presser-foot is carried by a plunger 18 and the latter is arranged to slide vertically in 85 guides 19, 19. A collar 20 is affixed to the plunger 18 and is provided with a pin 21 (Fig. 2) which is engaged by a forked lever 22. This lever is in the form of a bell-crank and is mounted upon a fulcrum stud 23. An 90 operating rod or link 24 is pivotally connected to the lever 22 and transmits motion from suitable operating mechanism 95 (not shown) to the presser-foot.

The hook-sustaining member is indicated 100 at 25. This member in the present instance is in the form of a plate, and it is affixed to a tilting support 26. Although the members 105 25 and 26 are made separately and put together, they are to all intents and purposes a unit and therefore may be considered collectively the hook-sustaining member. The hook-sustaining member is pivotally mounted upon a vertically movable carrier 27 by means of a pivot pin 28. The carrier 27 is 110

provided with cam rolls 29 and 30 which coact respectively with cams 31 and 32. These cams are carried by a shaft 33. The cam 31 raises and the cam 32 depresses the carrier 27. When the carrier is fully depressed the hook-sustaining member stands in register with the delivery end of a raceway 34. This raceway is one element of the hook-feeding means.

10 Any suitable mechanism may be employed for feeding lacing hooks one at a time to the raceway 34. Fig. 2 shows a feeder 35 for this purpose, and this figure includes also a feeder 36 by which the lacing hook α is pushed from the delivery end of the raceway to the plate 25 of the hook-sustaining member. No further description of the hook-feeding means will be necessary for the purposes of the present invention.

15 The purpose in mounting the hook-sustaining member upon a pivot as indicated at 28 is to enable it to be tilted to withdraw it from the set hook. The withdrawing motion is accomplished by a cam 37 on the 25 shaft 33, and the return motion is accomplished by one or more springs, two companion springs 38 (Fig. 1) being shown in the present instance. Titling motions are transmitted to the hook-sustaining member 30 by a link 39. The upper end of this link is connected to the hook-sustaining member by a pivot pin 40. As shown by Fig. 1 the link is provided with an elongated slot 41, and the shaft 33 extends through this slot so as 35 to engage the straight vertical surfaces thereof to guide the link. The link carries a cam-roll 42 which coacts with the under side of the cam 37. The springs 38 are attached to the link 39 in such manner as to maintain 40 an upward stress on the link, thus keeping the roll 42 in contact with the cam 37 and causing the hook-sustaining member to tilt from the angular position shown by Figs. 2 and 5 to the upright position shown by 45 Fig. 4 in keeping with the formation of the cam. In order, however, to limit the tilting movement of the hook-sustaining member to hook-receiving position, the hook-sustaining member is provided with a pin 43 (Fig. 2) 50 which projects laterally so as to coact with a stop shoulder 44 on the carrier 27.

The hook-sustaining member describes the following movements: Assuming that a hook has just been set as shown by Fig. 4 and that 55 the setting tool has been raised enough to relieve the pressure upon the set hook, the cam 37 depresses the link 39, thus tilting the hook-sustaining member to the position shown by Fig. 5. The plate 25 of the hook-sustaining member is thus withdrawn from the set hook. The carrier 27 is then depressed by its cam 32 to carry the hook-sustaining member into register with the delivery end of the raceway 34, and while 60 such movement is occurring the cam 37 per-

mits the hook-sustaining member to tilt to its upright position under the influence of the springs 38. The feeder 36 is then moved forward to push the hook from the raceway 34 to the plate 25, but if by any chance the plate 25 is slightly out of register, or if the lacing hook is imperfect in any respect which would prevent it from taking the desired position upon the plate 25, the hook-sustaining member would yield under the 75 stress of the feeder 36 and obviate the possibility of breaking or otherwise injuring the mechanism and obviate also the possibility of placing the hook incorrectly upon the plate 25. Assuming, however, that no such 80 difficulty arises, the carrier 27 will in due course rise with the hook-sustaining member in the angular position shown by Fig. 4 and will thus cause the shank of the lacing hook to pass through the stock α and engage 85 the setting tool.

The plunger 12 which carries the setting tool has a head 45 at its upper end, and this head is formed with a horizontal groove 46. A wrist-pin block 47 is arranged to slide in 90 the groove and is bored for the reception of the wrist-pin indicated at 48. This pin is carried by a disk 49 which is formed upon or affixed to the forward end of a rock-shaft 50. Referring now to Fig. 6, the rock-shaft 50 carries at its rear end a disk 51 on which is formed or in which is set a wrist-pin 52. A connecting rod 53 is fitted to the wrist-pin 52 and its lower end is formed with a slot 53' (Fig. 7) through which the 100 cam shaft 33 extends. The straight vertical surfaces of the slot engage the shaft and the longitudinal movements of the rod are guided by this means. The rod 53 carries cam-rolls 54 and 55 which coact respectively with cams 56 and 57. Cam 56 imparts downward movement to the setting tool and cam 57 imparts upward movement. Referring to Fig. 7, the high portion 58 is the portion which causes the punch 11 to 105 punch the hole in the stock. Referring to Fig. 9, line b indicates the angular position of the wrist-pin 48 when the setting tool is at its highest position. The punching motion of the wrist-pin is from line b to line 110 c . The cam 57 has a depression 58' which is the counterpart of the punching portion 58. As soon as the punching motion has been completed the punch is raised slightly by the point 59 of cam 57 to relieve the pressure of the punch upon the punch block but not enough to withdraw the punch from the hole in the stock. Referring again to Fig. 9, the angular motion of wrist-pin 48 caused 115 by cam portion 59 carries the wrist-pin from line c to line d . The concentric portions 60 and 60' of these two cams maintain the punch in the stock as last described for a sufficient length of time to enable the punch to move laterally to feed the stock into 120 125 130

hook-receiving position, and to sustain the setting tool in setting position while the hook-sustaining member rises to insert and clench the hook.

5 When the hook-setting members have reached the relative positions shown by Fig. 4 the shoulder 61 of cam 57 is about to engage the roll 55 to raise the setting tool to the position shown by Fig. 5. Referring 10 again to Fig. 9, the corresponding movement of wrist-pin 48 is from line *d* to line *e*. The depression 61' (Fig. 7) is the counterpart of shoulder 61. This shoulder 61 raises the setting tool enough to relieve the pressure 15 of the latter upon the set hook but not enough to withdraw the punch from the shank of the hook, and when the setting tool has been thus raised the hook-sustaining member is withdrawn from the hook as 20 hereinbefore described. After the hook-sustaining member has been withdrawn from the hook the setting tool is raised by the portion 62 of cam 57 which, according to Fig. 9, carries wrist-pin 48 from line *e* 25 to line *b*, whereupon the sliding carriage 14 is moved to the right from the position shown by Fig. 1 preparatory to repeating the punching motion.

30 The mechanism for reciprocating the feed carriage 14 is not of special importance so far as this invention is concerned, but may

be described briefly as far as it is shown. Referring to Fig. 3, the feed carriage is provided with a toothed rack 63. This rack is engaged by a spur-gear segment 64. An other spur-gear segment 65, formed upon or affixed to the segment 64, is engaged by a toothed rack 66. The latter is carried by a bar 67 which is arranged to slide back and forth. The bar 67 transmits motion from 40 suitable cams (not shown), said cams being timed to cause the feed motion and the return motion to occur as hereinbefore stated.

I claim:

In a hook-setting machine, a carrier, a 45 hook-sustaining member pivotally mounted thereon, a setting tool arranged to coact with said hook-sustaining member to set a hook, hook-feeding means, means arranged to move said carrier to carry a hook from 50 said hook-feeding means to said setting tool, a link pivotally connected to said hook-sustaining member, a spring attached to said link and arranged to act thereon to tilt said hook-sustaining member to hook-sustaining 55 position, and a cam arranged to act on said link to retract said hook-sustaining member from hook-sustaining position.

In testimony whereof I have affixed my signature.

FREDERICK W. LUSCOMB.
